UNITED STATES PATENT OFFICE.

PAUL B. MURPHY, OF NYACK, NEW YORK, ASSIGNOR, BY MESNE ASSIGNMENTS, TO
WESTERN ELECTRIC COMPANY, INCORPORATED, A CORPORATION OF NEW YORK.

SIGNAL-RECEIVING SYSTEM.

Application filed February 9, 1925. Serial No. 7,745.

This invention relates to signaling systems and more particularly to a signal receiving system for interpreting alternating current signals.

5 An object of the invention is to receive and interpret in a manner to produce a uniform effect, differently attenuated high frequency alternating current signals. In signal transmitting and receiving systems where high 10 frequency alternating currents are used as the signal transmitting medium and the signals are composed by interrupting these currents at different rates to produce different codes it is highly desirable that the receiving 15 equipment shall respond quickly and function in a uniform manner in response to the signals even though the strength of such signals may vary due to various causes such as the attenuations caused by different 20 lengths of transmission line over which the signals may be transmitted.

To attain this and other objects of the invention, there is provided in accordance with one feature of this invention means including a space discharge device for producing a uniform effect in a relay or in the secondary of a transformer or any other similar type of apparatus from differently attenuated signals impressed upon the input circuit 30 of said device.

Another feature of the invention is the arrangement of the input circuit and the output circuit of a space discharge device as to produce in the output circuit a uniform 35 effect from differently attenuated signals impressed on the input circuit.

Another feature of the invention is the provision of means in the input circuit of a space discharge device whereby a potential 40 set up in the input circuit, due to the flow of electrons between the filament and the grid when the voltage of the incoming signals is increased above a certain value, is utilized to counteract the effect produced in the output 45 circuit by the incoming signals and thereby to maintain the effective output of the receiving circuit at a constant value.

Another feature of the invention is the provision of means in a space discharge device arranged for uniform output for preventing self-oscillation although the output 50 and input circuits are inductively coupled. This is done by an arrangement for actually short circuiting the output circuit to currents of the high frequency to which the in-

put circuit is made responsive and also by short-circuiting the input circuit to currents of the low frequency to which the output circuit is made responsive.

Referring now to the drawings, Fig. 1 60 illustrates one form of the invention as applied to a system in which high frequency alternating signals are transmitted over a line to cause the uniform operation of a relay through a receiving circuit, involving a 65 space discharge device employed as an amplifier and another space discharge device employed as a rectifier; while Fig. 2 illustrates another form of the invention where the rectifying space discharge device is employed to cause a uniform effective output 70 through a transformer, one winding of which is included in the input circuit and another winding of which is included in the output circuit of said device. 75

Referring now specifically to Fig. 1, the transmission line 1 is connected at the transmitting end to the transmitter 2 including a source of high frequency alternating current source 3 and a manually operated key 4 in the primary circuit of a transformer 5, the secondary winding of which is included in the transmission line 1. It should be noted that several transmitters such as 2 having 80 sources of alternating current of different 85 high frequencies may be connected to the transmission line 1 by means of taps, such as are shown at 6. At the receiving end of the transmission line 1 a complete receiving circuit 10 is shown. This receiving 90 circuit includes a transformer 11, a space discharge device 12 acting as an amplifier, another space discharge device 13 acting as a rectifier to the incoming signals, and a relay 14, the actions of which may be controlled by the amplified incoming signals in a uniform manner in accordance with the principles of this invention embodied in this circuit, as will be presently described.

Taps such as 15 from the transmission line 1 indicate that other receiving circuits, such as 10, may be connected to the line for the reception of signals of different frequencies, each receiving circuit being arranged to respond to signals received from a high frequency alternating current source of a different transmitter, that is, signals from the transmitter 2 may be received by the receiver 10, which is arranged to exclude signals from other transmitters, while a re- 100 105 110

ceiver attached to taps 15 may respond only to signals from a transmitter attached to taps 6.

The operation of this system as illustrated in Fig. 1 is as follows:

The operation of key 4 in accordance with a desired code will, as is well known in the art, cause corresponding impulses of high frequency alternating current from source 3 to be induced in the line 1 through the transformer 5. Such signals may, if the length of line is long, be received at 10 greatly attenuated, while if the line is short they may be received at 10 but slightly attenuated. It should be understood that the arrangement may be such that the stations provided with transmitters and receivers may be located at varying distances from each other. Hence, the transmission line 15 over which the signals are transmitted and, therefore, the attenuation of the signals may vary. Moreover, each transmitter and its corresponding receiver may be connected to different lines through suitable switching arrangements such as manual plugs or jacks, or machine switching apparatus, and each of these lines may attenuate the transmitted signals differently.

In accordance with the invention, the means provided in connection with the receiving circuit 10 cause the greatly attenuated signals to produce the same effect in the receiver as signals less attenuated. That is, relay 14 is caused to act with practically the same magnetic pull regardless of the strength of the incoming signals. Hence, if this relay 14 has been once adjusted to respond properly to the weakest incoming signals likely to be received, it will also respond without any other adjustment in practically the same characteristic manner to incoming signals of greater strength such as will ordinarily be received over the shorter lines.

In order to make this action clear, it will at first be assumed that the incoming signals are greatly attenuated. The greatly attenuated high frequency alternating current signals will then be received through the transformer 11 and amplifier 12 in the usual manner well known in the art and be impressed through the condenser 17 and the input circuit of tube 13 on the grid 18. Because of the great attenuation in the signals, the applied alternating current voltage on the grid 18 will be of comparatively low magnitude. In fact, the magnitude of the positive half wave of the applied alternating current voltage will under these circumstances be less than the normally maintained negative grid potential. The grid 18 being maintained negative in respect to the filament 20 by the usual C battery 19, such incoming signals will therefore merely cause the grid 18 to become more or less negative and thus

produce in the usual manner corresponding fluctuations of the current in the output circuit of tube 13. The output circuit of tube 13, which is connected through one winding of relay 14 and battery 22, is also connected through a condenser 23 to ground, and the resulting current in this circuit is thereby caused to be greatly stabilized. As is well known, the interaction between the condenser 23 and the battery 22 may be made such that a practically constant current will pass through the left hand winding of relay 14 for each high frequency alternating current signal received over the line. Relay 14 will therefore normally be adjusted to respond to these signals and operate its armature to produce the desired signaling effects as, for example, to break and make the energizing circuit for sounder 24 and cause it to reproduce the code.

The characteristics of the anti-resonant circuit 25 are such as to cause the tube 13 to be made responsive only to alternating current of a particular high frequency, as is well known in the art. Hence, only the current in the output circuit produced by this particular frequency will determine the action of relay 14 provided, of course, that the incoming signals are greatly attenuated.

It is essential that this relay 14 or any other similar signal responsive device should maintain these operating characteristics regardless of changes in intensity of the incoming signals and without adjustment to compensate for varying attenuations. If, therefore, the relay is adjusted principally to operate properly in response to a certain pull on the armature when the current in the output circuit of the tube 13 is of minimum strength it should also in accordance with this invention exert practically the same pull when the current in the output circuit is of intermediate strength or of the maximum strength that may be obtained in practice when other transmission lines are used with this receiving circuit.

To this end, a branch of the input circuit is connected through the right hand winding of the relay 14 so that if a current is produced in this circuit it will pass through this winding in such a direction that the magnetic flux caused thereby will counteract that produced in the left hand winding by the current in the output circuit. The magnitudes of these currents will always have a certain proportional relation to each other so that when the transmission line connected to the receiver is comparatively short and the attenuations of the incoming signals are correspondingly small, the resulting magnetic pull on the armature will be practically the same as when the line is long and the attenuations of the signals correspondingly greater. To produce such current in the input circuit from the less at

attenuated high frequency signals, it should be remembered that the applied alternating current voltage on the grid 18 must be such as to make the grid positive in relation to 5 the filament 20, and this will happen if the magnitude of the positive half wave of the applied voltage is greater than the normal negative potential of the grid. The grid will then become positive to an amount 10 equal to the difference between the applied positive potential and the normal negative potential of the grid.

It is readily seen that if this is the case, a corresponding current will flow between 15 the grid and the filament in a direction to oppose the battery 19. If it is assumed then that the applied alternating current voltage is greater than the normally maintained negative potential, the current flowing 20 in the output circuit will also assume a greater magnitude, and these two currents in the output and the input circuits will produce counteracting flux in the relay 14 so proportioned that the resulting magnetic 25 pull on the armature will be approximately the same for any signals regardless of their magnitude.

As is well known in the art, oscillatory effects are generally produced when the output 30 and input circuits are coupled together in space discharge devices of this type, and it now remains to be explained how such effects may be prevented in the tube 13. These effects may in accordance with this 35 invention be avoided first by making the capacity of the condenser 23 such that it will afford a low impedance or act practically as a short circuit to the high frequency fluctuations in the output current, and therefore 40 decrease the inductive effect that may ordinarily be produced by such fluctuations in the input circuit through the windings of the relay 14; and secondly, by making the anti-resonant circuit 25 of such low 45 impedance as to act as a practical short circuit to the low frequency that may be induced through the windings of relay 14 from the lower rate interruptions in the output current, as produced by the incoming 50 code signals. In this manner, therefore, any oscillatory effects that may ordinarily be set up between the input and output circuits in this device are entirely eliminated.

The modification of the invention shown 55 in Fig. 2 differs from the arrangement of Fig. 1 only in that a three-winding transformer 30 is substituted for the relay 14 of the previous figure, the input circuit of the tube 13 being wired through one winding 60 31 of this transformer, the output circuit being wired through another winding 32 of the transformer, and a third winding 33 of the transformer being connected to an outgoing circuit. This arrangement operates 65 in a manner similar to the arrangement

described in connection with the previous figure to produce an effective uniform output from the tube 13 irrespective of amplitude variations in the input currents to the tube.

It should be understood that the invention is not limited to the particular arrangements of the output and input circuit shown in these two figures but that they merely serve as an illustration of the principles involved, and that any other devices similar to the relay 14 or transformer 30 may be employed in connection with the input and output circuits for obtaining a uniform effective output current.

What is claimed is:

1. The method of equalizing the effects of alternating signaling currents of different strengths on a receiving device, which comprises transmitting current variations 85 corresponding to the received signaling currents through branched paths having different volt-ampere characteristics, the characteristics of the paths being such that for weak incoming signaling currents the current output of one of said paths predominates over the current output of the other path in a certain ratio and for stronger received signaling currents said certain ratio 90 of the current outputs of the two paths is substantially maintained and opposing the outputs of said paths upon the receiving device.

2. A circuit for receiving alternating current signals of different strengths, comprising two branched paths of different volt-ampere characteristics for transmitting current variations corresponding to the received alternating signaling currents, the characteristics of said paths being such that for weak incoming signaling currents the current output of one of said paths predominates over the current output of the other path in a certain ratio, and for stronger received signaling currents said certain ratio 105 of the current outputs of the two paths is substantially maintained, a receiving device, and means for impressing the outputs of said two paths in opposition upon said receiving device.

3. A circuit for receiving alternating signaling currents of different strengths, comprising two branch paths of different volt-ampere characteristics for transmitting current variations corresponding to the received signaling currents, the characteristics of said paths being such that for weak incoming currents the current output of one of said paths predominates over the current output of the other of said paths by a given amount, and for stronger incoming currents the current outputs of the two paths also differ by substantially said given amount, said one path including the plate-filament circuit of a 120 space discharge device, said other path in- 125

cluding the grid-filament circuit of the same space discharge device, means to oppose the outputs of said two paths, and means responsive to the resultant effect of the opposing outputs.

4. A receiving circuit adapted for receiving alternating current signals of different strengths, comprising a space discharge device having a filament, a plate and a grid electrode, two paths of different volt-ampere characteristics, one of said paths including the grid and filament of said space discharge device, the other of said paths including the plate and filament of said space discharge device, means for impressing the received alternating current signals on said paths in parallel, the characteristics of said paths being such that for weak incoming signaling currents, the current output of said one path is smaller than the current output of said other path in a certain ratio, and for stronger incoming signaling currents said certain ratio of the current outputs of said paths is maintained and means to oppose the outputs of said paths comprising a relay having two inductively related windings one of said windings being in said one path and the other in said other path.

5. In a signaling system, the combination of means for transmitting high frequency alternating current signals over lines having different characteristics, whereby the signals received at the far ends of said lines are differently attenuated, with a receiver for such attenuated signals comprising a space discharge device, an input and output circuit thereof, a relay having one winding in the input circuit and another winding in the output circuit, and means associated with said circuits for producing the same magnetic pull by said relay from any of said attenuated signals received regardless of their varying degree of attenuation.

6. In a signaling system, a receiver for differently attenuated high frequency alternating current signals comprising a space discharge device, an input and an output circuit therefor, a relay having one winding in the input circuit and another winding in the output circuit of said device, and means associated with said circuits and said space discharge device for producing a certain electromagnetic pull by said relay when the received signal characteristics are such as to cause said relay to be influenced only by currents produced thereby in the output circuit, and for producing substantially the same electromagnetic pull by said relay when the received signal characteristics are such as to cause said relay to be influenced by currents produced thereby in both the input and the output circuits.

7. In a signaling system, a combination of means for transmitting high frequency alternating current signals over lines having

different characteristics, whereby said signals when received at the far ends of said lines are differently attenuated, with a receiver therefor comprising a space discharge device, an input and an output circuit therefor, a transformer having one winding in the input circuit and another winding in the output circuit of said device, and means associated with said circuits and the transformer for producing substantially uniform alternating current signals from any signals received regardless of the individual attenuations thereof.

8. In a signal receiving system, a space discharge device having its input circuit inductively coupled to its output circuit, and means for substantially eliminating self-oscillatory effects in said device that may tend to be produced by said inductive coupling, said means including means in said input circuit and independent means in said output circuit.

9. In a signal receiving system, a space discharge device having its input and output circuits inductively coupled, and means including a condenser to ground in the output circuit for substantially eliminating oscillatory effects from said device that may tend to be produced by said coupling.

10. In a signal receiving system, a space discharge device having input and output circuits inductively coupled so as to tend to produce self-oscillatory effects, and means in said output circuit for substantially preventing such self-oscillatory effects from taking place.

11. In a signaling system, means for receiving differently attenuated alternating current signals comprising a space discharge device, an output and an input circuit therefor, a relay having one winding in the output circuit and another winding in the input circuit so arranged that said circuits are inductively coupled and so that currents produced in said circuits from any of said signals when received by said device will produce substantially the same electromagnetic pull by said relay, and means for eliminating self-oscillatory effects in said device that may tend to be produced by the inductive coupling of said circuits.

12. In a signaling system, a receiver for differently attenuated alternating current signals, comprising a space discharge device, an output circuit and an input circuit therefor, a relay, means involving the inductive coupling of said output circuit and input circuit for producing a substantially uniform electromagnetic pull by said relay from any of said differently attenuated signals when received by said device, and means including a condenser one side connected to ground and the other to the output circuit and an anti-resonant circuit included in said input circuit, for preventing self-oscillatory

effects in said device, that may tend to be produced by the inductive coupling of said circuits.

13. In a signaling system, a receiver for 5 differently attenuated high frequency alternating current signals comprising a space discharge device, an output and an input circuit inductively coupled together, and means effective through said coupling of the input 10 and output circuits for producing substantially uniform high frequency alternating current signals from any of said received signals regardless of their attenuation, and means included in said input and output circuits 15 for eliminating any self-oscillatory effects in said device that may tend to be produced due to said inductively coupled circuits.

14. In a receiving circuit including a space 20 discharge device having its input and output circuits so related to each other as to subject the device to regenerative effects when said device is subjected to differently attenuated current impulses, means for substantially 25 eliminating such effects comprising a means in the input circuit for preventing said input circuit from being responsive to frequencies to which the output circuit is responsive, and means for making said output circuit responsive only to frequencies other than those to which the input circuit 30 is responsive.

15. In a signaling system, a source of incoming waves consisting of a high frequency 35 wave modulated by a wave of lower frequency, a space discharge device arranged to function as a rectifier, said space discharge device having input and output circuits inductively coupled to each other, said input 40 circuit being supplied with said incoming waves, and means to prevent self-oscillatory effects in said device due to the inductive coupling between the input and output circuits, said means comprising means in said 45 input circuit for making said input circuit selectively responsive to the modulated frequency and means for making the output

circuit responsive only to the modulating frequency.

16. In a signaling system, a source of 50 waves of varying energy level, a current regulating current-responsive receiving device therefor comprising a space discharge tube having a cathode, a grid and an anode, an inductance winding in each of the circuits respectively connecting the cathode to the grid and the cathode to the anode, said windings being magnetically interlinked, means for impressing said waves upon the circuit connecting said cathode to said grid, 60 means in said circuits responsive to said waves for insuring that the resultant current flowing in one of said circuits through the inductance winding therein bears substantially the same relation to the current flowing in the other of said circuits through the inductance winding therein for all energy levels of said impressed waves, and means responsive to the differential effects of current flow through said windings for producing a uniform effect. 65

17. In combination, a space discharge device having cathode, anode and impedance control elements, an input and an output circuit therefor, means to impress waves of 70 varying amplitude on the input circuit of said device, an outgoing circuit, and means for causing said waves of varying amplitude to produce substantially identical effects in 75 said outgoing circuit, comprising means for coupling the input and output circuits of said device, means responsive to the impressed waves for producing currents in the input and output circuits, respectively, bearing at all times a definite, constant relation 80 to each other, and means differentially controlled by said currents in said input and output circuits for controlling said outgoing circuit. 85

In witness whereof, I hereunto subscribe 90 my name this 6th day of February A. D., 1925.

PAUL B. MURPHY.
